CLAIM

The ornamental design for a portion of a footwear upper, as shown and described.

DESCRIPTION

FIG. 1 is a side perspective view of a portion of a footwear upper showing my new design;

FIG. 2 is a side elevational view thereof;

FIG. 3 is an opposite side elevational view thereof;

FIG. 4 is front elevational view thereof;

FIG. 5 is rear elevational view thereof;

FIG. 6 is a top plan view thereof;

FIG. 7 is a bottom plan view thereof;

FIG. 8 is a side perspective view thereof in a folded down position;

FIG. 9 is a side elevational view thereof;

FIG. 10 is an opposite side elevational view thereof;

FIG. 11 is front elevational view thereof;

FIG. 12 is rear elevational view thereof;

FIG. 13 is a top plan view thereof; and

FIG. 14 is a bottom plan view thereof.

FIG. 15 is a side perspective view of a second embodiment of a portion of a footwear upper showing my new design;

FIG. 16 is a side elevational view thereof;

FIG. 17 is an opposite side elevational view thereof;

FIG. 18 is front elevational view thereof;

FIG. 19 is rear elevational view thereof;

FIG. 20 is a top plan view thereof;

FIG. 21 is a bottom plan view thereof;

FIG. 22 is a side perspective view thereof in a folded down position;

FIG. 23 is a side elevational view thereof;

FIG. 24 is an opposite side elevational view thereof;

FIG. 25 is front elevational view thereof;

FIG. 26 is rear elevational view thereof;

FIG. 27 is a top plan view thereof; and,

FIG. 28 is a bottom plan view thereof.

The broken lines in FIGS. 1-28 represent portions of the footwear that form no part of the claimed design.
